UNITED STATES PATENT OFFICE.

JAMES V. ADAMS, OF YOWELL, TEXAS.

GASOLINE WASH FURNACE.

Application filed September 20, 1921. Serial No. 502,024.

To all whom it may concern:

Be it known that I, JAMES V. ADAMS, a citizen of the United States, residing at Yowell, in the county of Delta and State of Texas, have invented new and useful Improvements in Gasoline Wash Furnaces, of which the following is a specification.

My present invention is primarily directed to an improved hydrocarbon burner.

10 My primary object is to produce a burner of this character which is especially designed for use in heating water for clothes washing purposes.

15 In carrying out my invention, it is my aim to arrange in the bottom of a casing for a wash boiler a hydro-carbon burner of a particular and peculiar construction through the medium of which the flame will be directed against the bottom and against 20 the sides adjacent to the bottom of the boiler, and thereby effectively heat the boiler to boil the water therein in an expeditious manner and with a small consumption of fuel, the flame of the burner being readily 25 regulated from the exterior of the boiler casing.

It is a still further object to produce a 30 hydro-carbon burner for clothes boilers in which gasoline will be vaporized in a quick and efficient manner and when ignited, the 35 flame thereof will be directed against the boiler in a manner to quickly boil the water therein, the burner being arranged in the casing which supports the boiler and therefore effectively housed to prevent burning 40 or other injury being inflicted to the attendant or to persons in close proximity thereto, while the construction is such as to positively obviate the liability of the explosion of the gasoline.

It is a still further object to produce a 45 gasoline wash furnace in which the boiler for the clothes is supported in a suitable casing, the latter having its base portion apertured for the admission of air and an 50 apertured bottom above the first mentioned apertures, the latter supporting thereon a hydro-carbon burner which includes a generating chamber that has upwardly curved 55 burner tubes extending from the sides thereof to receive therebetween the bottom of the boiler, while on the exterior of the casing, adjacent to the top thereof, there is supported the gasoline tank that has a delivery pipe leading to vaporizing tubes disposed over the top of the burner, the outlet

member of the said tube communicating with a compartment on one side of the generating chamber, the top of the chamber having a continuous irregularly shaped depression disposed between the members comprising the vaporizing tube, the said depressions forming a duct for the reception of gasoline which is let therein through a valve controlled port in the compartment, the gasoline in the said duct being ignited to vaporize the fuel in the vaporizing tubes, permitting the vapor to enter the compartment, and thereafter to be directed through a valve controlled pipe through an opening in the bottom of the compartment, the top of the compartment between the ducts being provided with apertures for the vaporized fuel.

The foregoing, and other objects which will appear as the nature of the invention is better understood, may be accomplished by a construction, combination and operative association of parts, such as is disclosed by the drawings which accompany and which form part of this specification.

In the drawings:—

Figure 1 is a side elevation of the improvement, parts being broken away and parts being in section.

Figure 2 is a top plan view of the burner.

Figure 3 is a section view, on the line 3—3 of Figure 2.

Figure 4 is a sectional view, on an enlarged scale, and approximately on the line 4—4 of Figure 2.

Referring now to the drawings in detail, the numeral 1 designates the clothes boiler. The boiler 1 is constructed of some suitable metal and has its lower and closed end rounded. The top of the boiler has a continuous bead 2, the under face of which providing a shoulder for the substantially frusto-conical hollow casting 3. The casing 3 is provided, adjacent to its lower end with a series of apertures 4, the same forming air inlets, while above the apertures there is secured in the casing the bottom plate 5. The plate 5 is also provided with spaced apertures 6 that admit air to the interior of the casing and to the bottom of the boiler. The casing has one of its sides provided with an opening that is normally closed by a door 7, the said door being arranged only a slight distance above the elevated base or bottom 5.

On one side of the casing, adjacent to the

top thereof there is an outstanding shelf 8 suitably braced, as at 9, and supporting thereon a gasoline tank or reservoir 10.

The improved hydro-carbon burner is arranged in and at the center of the casing 3, the same being supported on legs 11 which elevate the same above the base or floor 5. The hydro-carbon burner has its body portion in the nature of a generating chamber 12. The chamber is in the nature of a casting, being preferably round in plan, and the same has upon its flat top a continuous depression, which defines central longitudinal passages 13 connected at their ends by rounded passages 14, the end longitudinal passages being connected by a curved passage 15 disposed adjacent to the rounded periphery of the chamber 12, while the innermost longitudinal passage, indicated for distinction by the numeral 16, communicates with a compartment 17 that is integrally formed on one side of the chamber 12. This branch 16 is in a line with a ported boss 18 that projects inwardly of the compartment 17, the said boss having its port flared inwardly from its inner end to provide a seat for a needle valve 19. The stem of the valve 19 is threaded and is received in a threaded boss 20 that projects from one of the sides of the compartment 17.

The stem of the valve 19 passes through a suitable opening in the casing 3, the said stem having its outer end provided with the usual operating handle whereby the valve 19 can be operated exteriorly of the casing 3.

The outlet pipe for the gasoline tank or reservoir is indicated by the numeral 21, and has an angle branch which passes through the casing 3, below the apertured elevated base or floor 5 thereof, the said passage indicated by the numeral 22 communicating with a vertically disposed extension 23 which has an angle branch arranged over the top of the generating chamber 12 and which may be integrally formed with or have connected thereto the vaporizing tube 24. The vaporizing tube 24 is shaped to substantially correspond with the depressions that provide the gasoline ducts 50 on the upper face of the generating chamber, that is the vaporizing tube comprises longitudinal branches connected by rounded branches, the outermost longitudinal branches being connected by a rounded branch of a greater circumference than the inner rounded branch, and the inner end of the tube, indicated for distinction by the numeral 25 communicates with the compartment 18. The compartment 18, has a bottom portion which projects below the generating chamber 12, and secured thereto there is a pipe 26 that has its outer end closed, but its top portion provided with one or more apertures 27 arranged directly over 60 a central opening 28 in the bottom of the

generating chamber 12. The top of the generating chamber is provided with spaced apertures 29 between the gasoline ducts thereon.

By reference to Figure 4 of the drawings, 70 it will be noted that the vapor outlet 27 is disposed a considerable distance away from the bottom of the generating chamber, so that air will freely mix with the vaporized gas before entering the chamber 12, and 75 by also referring to the said Figure 4, it will be seen that the vapor conducting pipe 26 is controlled by a needle valve 30, the said valve having a threaded stem which is received in the threaded bore of a boss 31 on 80 one of the sides of the compartment 17. The stem of the valve 30 passes through an opening in the casing 3, the outer end of the said stem being provided with an operating head or handle.

The sides of the generating chamber are provided with any desired number of spaced threaded openings, and in each of these openings there is screwed a burner tube 32. Each burner tube is directed upwardly in 90 the casing 3, the burner tubes being disposed to receive therebetween the lower rounded end of the boiler 1. The tubes 32 have their outer ends closed by plugs 33 and their inner faces are apertured, as at 34.

The operation of the device may be briefly described as follows:

The gasoline flows from the tank or reservoir 10 so that a part thereof is at all times received in the compartment 17. By opening the needle valve 19, a quantity of the gasoline will be permitted to enter the ducts provided by the depressions in the top of the generating chamber. The valve is then closed and the gasoline which is received in the depressions, that really provide the gasoline trough, is ignited, the flame thereof being directed against the coiled vaporizing tubes, generating the fuel which passes through the said tubes. This fuel 100 enters the compartment 17, and the valve 30 is unseated permitting the said fuel to pass through the conductor pipe 26, port 27 and opening 28 into the generating chamber 12. The fuel will pass through the openings 29 110 and through the burner tubes 32. The ignited gasoline in the ducts will light the fuel that passes through the openings 29 and through the apertures in the burner tubes, and it will be thus noted that the 120 flames will be positively directed against the bottom and also against the sides adjacent to the bottom of the boiler 1. The flame can be regulated by adjusting the valve 30, and it is thought that the foregoing description, 125 when taken in connection with the drawings will fully set forth the construction, operation and advantages of the improvement to those skilled in the art to which such inventions relate. It is to be understood, how- 130

ever, that the nature of the invention is such as to render the same susceptible to changes, and therefore I am not to be restricted to the precise structure illustrated and described, 5 but am entitled to make all such changes therefrom as fall within the scope of what I claim.

Having described the invention, I claim:

1. In a hydro-carbon burner, a hollow casting having an apertured top and said top on its outer face provided with communicating, irregularly shaped grooves which provide a trough for gasoline, means controlling the gasoline fed into the trough, 10 a vaporizing tube above the chamber, means introducing a gaseous fluid therethrough and the said tubes designed to be heated by the ignition of the gasoline in the trough, said chamber having a compartment re- 15 ceiving the vapor from the tubes, an outlet pipe for the chamber for delivering the gas through the bottom of the chamber, a valve controlling the passage through said pipe, and outwardly directed upwardly curved 20 25 apertured burner tubes on the sides of the chamber.

2. In combination with a boiler, a casing supporting the same having air inlet openings adjacent to the bottom thereof and an apertured base above said openings, of a 30 hydro-carbon burner including a hollow casting supported above the base, said casting having an apertured top and having circu- 35 lous depressions on the outer faces thereof, said casing having a compartment on one 40 side thereof communicating with said de- pression, a valve controlling said communi- cation, a vaporizing tube of a contour of that of the depression arranged above the chamber and communicating with the com- 45 partment, means delivering gasoline into the vaporizing tube, a fuel outlet pipe for the compartment communicating with the bottom of the chamber, but spaced there- from, a valve controlling said communica- 50 tion, and upwardly directed apertured burner tubes secured to the sides of the casing and disposed to surround the base and sides of the boiler at the base portion thereof.

In testimony whereof I affix my signature.

JAMES V. ADAMS.
